[57] CLAIM

The ornamental design for an optical disc storage library, as shown and described.

DESCRIPTION

FIG. 1 is a top, front, and right-side perspective view of an optical disc storage library, showing our new design; FIG. 2 is a top, front and left-side perspective view thereof;

FIG. 3 is a top, front and right-side perspective view thereof, shown in the open position;

FIG. 4 is a front elevational view thereof on an enlarged scale;

FIG. 5 is a left-side elevational view thereof;

FIG. 6 is a right-side elevational view thereof;

FIG. 7 is a top plan view thereof; and,

FIG. 8 is a bottom plan view thereof.

FIG. 1

FIG. 2
